UNITED STATES PATENT OFFICE.

FRANK C. MILLER, OF PROVIDENCE, RHODE ISLAND, ASSIGNEE TO CHILD & MILLER CO., OF PROVIDENCE, RHODE ISLAND, A CORPORATION OF RHODE ISLAND.

COMBINED VANITY-CASE AND MESH-BAG.

1,111,397.

Specification of Letters Patent. Patented Sept. 22, 1914.

Application filed November 3, 1913. Serial No. 798,855.

To all whom it may concern:

Be it known that I, FRANK C. MILLER, a citizen of the United States, residing at Providence, in the county of Providence and State of Rhode Island, have invented a new and useful Improvement in Combined Vanity-Cases and Mesh-Bags, of which the following is a specification.

This invention relates to certain new and useful improvements in combined vanity cases and mesh bags, and the primary object of the invention is to provide a mesh bag which has incorporated in the head or top portion thereof a vanity case, which latter, more particularly, is formed in two sections or parts, one section or part being on one side of the head of the bag, while the other section or part is on the other side of the head of the bag.

Further, the invention aims to provide a vanity case which is incorporated in the head of a bag so as to be normally concealed, and still capable of being readily opened to enable access thereto.

In the drawing:—The figure is a perspective view of the invention, showing all of the parts in open position.

The hand bag is formed with the usual mesh fabric body 1, and a head formed of hinge parts or sections 2 and 3, which parts are held in closed position by any suitable latching or locking device 4. Each part or section of the head of the bag is formed with a depression 5, and a lateral recessed portion 6 which extends through one end of the depression 5 and through the adjacent head or section, a plate or closure 7 being hinged at the opposite end of the depression 5 so as to lie flush with the inner faces of the sections or parts when the closure is in operative position. Each closure 7 has an arm 9 which is conformably received in the recessed portion 6, the outer ends of the arms 9, being provided with hooks 10 which are adapted to snap over the adjacent ends of the sections or parts. From the above it will be apparent that when the closures are in closed position, same will lie flush with the inner faces of the sections or parts and thus conceal the depressions 5 and recessed portions 6, imparting to the inner faces of the parts or sections a substantially smooth appearance. The recessed portion 5 of the head or section 2 is provided with a

mirror 11 and also a looped part 12 which is adapted to receive and retain a pencil 13. The depression 5 may be made sufficiently deep so as to allow of a memorandum pad being placed therein in overlying relation to the mirror and pencil, so that the pad may be retained in the depression by the closure 7. The depression 5 of the part or section 3 is provided with a powder puff receptacle 14 and other smaller depressions or wells 15 in which cosmetics may be placed. The depression 5 may also be provided with a circular recessed part or depression 16 to provide a coin holder. It will be understood that the character of the articles which it may be desired to place in the depressions 5 may vary, and accordingly variation in the characters of the holders which retain the articles is thereby necessitated in order to provide the required conformity.

From the above it will be seen that in accordance with this invention the various articles which constitute a vanity case are incorporated in the head portion of a bag and normally concealed therein, so that the bag presents substantially the same appearance possessed by the well known and commonly used mesh fabric bags. Of course it will be understood that the head portion of the bag may be made large or small in accordance with the total number of vanity articles which it is desired to have the bag hold or contain.

Having thus described my invention, I claim as new and desire to secure by Letters Patent;

1. In a hand bag, a head portion having a pair of parts and having a depression in one of its parts, and also having a lateral recessed portion which communicates with one end of the depression and extends through the adjacent end of said head portion part, a closure for the depression hinged adjacent to the other end of the latter, and an arm having a snap hook on its free end carried by the closure and adapted to be received in the recessed portion and to have its snap hook engaged with the adjacent end of the head portion part, said closure and arm thereof then extending substantially flush with the inner face of the head portion part.

2. In a hand bag, a head portion having a pair of parts and having each of its parts

provided with a depression and a closure for each depression hinged to the respective head part and having a snap hook to engage over the adjacent end of the head part.

5. 3. In a hand bag, a head portion formed of two similar parts, one of said parts having a depression, and an openable closure for said depression, said closure extending flush with the inner face of the head part which 10 carries same to thereby allow the inner face of the other head part to contact with the inner face of the first named head part and to completely conceal the closure.

4. In a hand bag, a head portion formed 15 of two parts, one of said parts having a depression, a hinged closure for said depression, and a snap hook carried by the closure

to engage over the adjacent end of said head part.

5. In a hand bag, a head portion formed 20 in two parts, one of the parts having a toilet article receiving depression which extends through the inner face of said part, and a closure for said depression, said closure, when the head portion is in closed position, 25 being covered by the inner face of the other part of the head portion.

In testimony whereof I have signed my name to this specification in the presence of two subscribing witnesses.

FRANK C. MILLER.
